UNITED STATES PATENT OFFICE.

DUNDAS DICK, OF NEW YORK, N. Y.

DESIGN FOR A MEDICINE-CASE.

SPECIFICATION forming part of Design No. 15,388, dated September 9, 1884.

Application filed July 5, 1884. Term of patent 7 years.

To all whom it may concern:

Be it known that I, DUNDAS DICK, a citizen of the United States of America, residing in the city of New York, in the county and State of New York, have produced a new and original Design for Medicine-Cases, of which the following is a specification, reference being had to the accompanying drawings, forming part of the same, in which—

10 Figure 1 is a side view, in elevation, of my case; and Fig. 2 is a central longitudinal section of the same.

15 The leading feature of my design is the special and peculiar form which I give to the case, as represented in the drawings, the body of the case between the lines *a* and *b* being a truncated cone, either rounded or plane at the smaller end, and the part *e* below the line *b*

being of the form represented in the drawings, the same being curved inward toward 20 the center from the line *b*, and then again outward, so that the extremity forms a head, *f*, giving to the whole case a graceful and agreeable appearance. The body of the base *B* is conical or tapering on the outside, to match 25 the taper of the outside of the cover *A*. Both are chambered.

What I claim as my invention, and desire to secure by Letters Patent, is—

The design for a medicine-case herein shown 30 and described, which consists of the truncated cone *A* *B*, the neck *e*, and head *f*, as specified.

DUNDAS DICK.
